DESIGN FOR A FINGERNAIL GUARD

Jean H. Kayer, Hollywood, Calif.

Application August 31, 1946, Serial No. 133,000

Term of patent 14 years

(Cl. D86—10)

To all whom it may concern:

Be it known that I, Jean H. Kayer, a citizen of the United States, residing in Hollywood, in the county of Los Angeles and State of California, have invented a new, original, and ornamental Design for a Fingernail Guard, of which the following is a specification, reference being had to the accompanying drawing, forming part thereof.

Fig. 1 is a top plan view of a fingernail guard, showing my new design.

Fig. 2 is a side elevational view.

Fig. 3 is a bottom plan view.

Fig. 4 is an end elevational view, looking from the right in Fig. 2.

I claim:

The ornamental design for a fingernail guard, substantially as shown.

JEAN H. KAYER.
